UNITED STATES PATENT OFFICE.

ALEXANDER HUTCHINSON, OF PARIS, FRANCE.

RUBBER SHOE.

SPECIFICATION forming part of Letters Patent No. 251,782, dated January 3, 1882.

Application filed August 20, 1881. (No model.) Patented in France July 23, 1881.

To all whom it may concern:

Be it known that I, ALEXANDER HUTCHINSON, a citizen of the United States of America, residing at Paris, in the Department of the Seine, in the Republic of France, have invented new and useful Improvements in Rubber Shoes, (for which I have obtained a patent in the Republic of France under date of July 23, 1881,) of which the following is a specification.

My invention has for its object the manufacture of a rubber shoe that in form and appearance shall be an exact imitation of the Chinese shoe, with its thick sole and without exceeding or materially exceeding its weight; and to that end the invention consists in the relative arrangement and combination of the various soles of the shoe with the upper and lining.

Figure 1 shows the rubber shoe in elevation, 20 and Fig. 2 a transverse section on line *x x* of Fig. 1.

In carrying out my invention I first attach to the form or last an insole, *a*, of fibrous rubber. Then I apply a lining, *b*, of knit fabric, 25 that is glued or cemented to the insole *a* and extends over the inner face of the upper *f*. Next I apply a felt sole of one or more thicknesses, according to the thickness it is desired to give to the sole, which felt sole *c* is firmly 30 connected to the lining *b* by means of a strip, *d*, of cotton, linen, or other suitable fabric, coated with rubber. This done, I surround the whole of the sole with a strip of fibrous rubber, *e*, in order to impart to the sole the necessary 35 rigidity; and, lastly, I apply the exterior sole, *g*, and the upper *f* in the same manner as is done with ordinary rubber shoes, after which the shoe is ready to undergo the usual process of vulcanization.

Instead of a felt sole, a sole of any other suitable light material—such as horse or other hair, or cork, or analogous substances—may be employed.

It will, of course, be understood that the 45 various thicknesses of the soles and linings may be varied, and yet preserve the greatest thickness for the intermediate light or felt sole,

while the upper may be made of any other material than rubber, such as cotton, wool, silk, or other like fabrics.

The felt or lighter intermediate sole is preferably compressed in order to give it the necessary stiffness; but the pressure applied should not be such as to deprive said sole of its lightness.

If desired, the shoe may receive, when finished, a coat of paint along the sole, the same as the Chinese shoe.

It will also be understood that the Chinese shoe may be constructed in this manner, and 60 that such construction may be adapted in the manufacture of boots.

I am aware that attempts have been made to manufacture rubber shoes in imitation of the Chinese shoe; but such attempts, so far as they 65 have come to my knowledge, have proven failures, inasmuch as they resulted in a product entirely too heavy, arising both from the materials employed and from the imperfectly-understood proportions of soles and their com- 70 bination with the other parts of the shoe.

I am also aware that cork, felt, and analogous materials have heretofore been employed for insoles, and I do not desire to claim such, broadly, nor do I desire to claim a shoe that 75 in form is like a Chinese shoe.

Having now described my invention, what I claim, and desire to secure by Letters Patent, is—

A rubber shoe composed of an upper, *f*, and 80 an outer sole, *g*, both of rubber, a fibrous-rubber insole, *a*, a lining, *b*, of knit fabric, a thick sole, *c*, of felt or other analogous light material, a retaining-strip, *d*, and the fastening strip or lining *e*, all combined and arranged 85 substantially as shown and described.

In witness that I claim the foregoing I have hereunto set my hand this 29th day of July, 1881.

ALEXANDER HUTCHINSON.
